UNITED STATES PATENT OFFICE.

GERALD W. HART, OF WEST HARTFORD, CONNECTICUT, ASSIGNOR TO THE HART MANUFACTURING COMPANY, OF HARTFORD, CONNECTICUT, A CORPORATION OF NEW JERSEY.

DESIGN FOR A SWITCH CONTACT MEMBER.

SPECIFICATION forming part of Design No. 35,620, dated January 28, 1902.

Application filed October 30, 1901. Serial No. 80,561. Term of patent 14 years.

To all whom it may concern:

Be it known that I, GERALD W. HART, a citizen of the United States, residing at West Hartford, Hartford county, Connecticut, have 5 invented and produced a certain new and original Design for a Switch Contact Member, of which the following is a full, clear, and exact description.

In the drawings, Figure 1 is a plan view of 10 a switch contact member embodying my new and original design, and Fig. 2 is an edge view of the member shown in Fig. 1.

The design comprises a central ring-like member A, surrounded by a larger ring-like

member B. These members A and B are concentric, but are shown as spaced apart. They are, however, connected at one side, as at C. D is an extension from the outer side of the ring B, the same being located opposite the connection C. 15 20

What I claim is—

The design for a switch contact member herein shown and described.

GERALD W. HART.
